CLAIM

The ornamental design for a fishing rod perch with improved swivel and fish strike indicator, as shown and described.

DESCRIPTION

FIG. 1 is a perspective view of a fishing rod perch with improved swivel and fish strike indicator according to the invention;

FIG. 2 is another perspective view thereof;

FIG. 3 is another perspective view of the design shown in use, with the broken line environment being for illustrative purposes only and forming no part of the claimed design;

FIG. 4 is a side elevation view, with the broken lines being for illustrative purposes only and forming no part of the claimed design;

FIG. 5 is a front elevation view shown in use, with the broken line showing of environment being for illustrative purposes only and forming no part of the claimed design;

FIG. 6 is an exploded perspective view;

FIG. 7 is a front elevation view, with the rear elevation view being a mirror image thereof; and,

FIG. 8 is an opposite side view.
